UNITED STATES PATENT OFFICE.

GEORGE W. WILLIAMS, OF NEW YORK, N. Y.

SELF-CLOSING MOUTH FOR BAGS.

SPECIFICATION forming part of Letters Patent No. 744,846, dated November 24, 1903.

Application filed August 27, 1903. Serial No. 171,022. (No model.)

To all whom it may concern:

Be it known that I, GEORGE W. WILLIAMS, a citizen of the United States of America, and a resident of New York city, county of New York, State of New York, have invented an Improved Self-Closing Mouth for Bags, of which the following is a specification.

The object of my invention is to provide a self-closing mouth for bags, such as tobacco-bags, particularly those containing granular tobacco, so that these bags will normally remain closed and prevent the spilling and loss of tobacco and yet may be readily opened by the mere pressure of the hand to allow the tobacco to be poured from the bag much in the manner in which the old-fashioned powder-flasks permitted powder to be poured from them when their caps had been removed.

In the accompanying drawings, Figure 1 is a side elevation showing my improved device applied to a tobacco-bag. Fig. 2 shows this self-closing mouth opened by pressure between the thumb and first finger. Fig. 3 is a view of the mouthpiece at right angles to Fig. 1. Fig. 4 is a plan view of Fig. 3. Fig. 5 is a section on line *a a*, Fig. 3. Fig. 6 is a similar view of a modification. Fig. 7 is a view of a modified form of lip for the mouthpiece. Fig. 8 is a detailed view of a further modification, and Figs. 9 and 10 show a still further modification before and after assembling.

The mouthpiece is composed of a tube *T*, of flexible material, preferably rubber, having two flanges *F F'* at one end, forming a circular notch around the lower end of the tube, and thus adapting it to receive the bag, where its upper gathered edge will be drawn taut by the usual tie-strings *t*, which may be wrapped around and under the upper flange to frictionally hold them, thus making it unnecessary to tie them.

To the upper opening of the tube *T*, I secure flexible lips *L L*, preferably shaped as segments of a circle, with their straight edges meeting centrally and their curved edges held under the influence of elastic means, shown in this instance as the tube *T* itself. By forming these lips *L L* of the shape described it is insured that pressure exerted as shown in Fig. 2 will bow the lips away from

each other and produce the opening through which tobacco or the like may be poured. In order to cause the tension of the elastic tube to close these lips, in addition to their own tendency to elongate and occupy a closed position, I preferably notch the outer sides of the lips at *n n*. It will be seen that these notches open when in the position of Fig. 2, thereby tensioning the rubber tube, which when the fingers are released will spring back into position shown in Fig. 4. As shown in Fig. 7, in place of these notches and segmental-shaped lips I may make lips substantially straight and pointed at the ends and provide them with central bridge-pieces *B B*. A rubber band placed around these lips in like manner will tend to return them to a closed position.

The tube *T* may be secured to the flanges *F F'* in various ways. In Fig. 5 I have shown it as reinforced by an interior bushing *C*, on which two separate flanges are secured. In Fig. 6 the two flanges *f f'* are shown formed together spool fashion and the tube secured within their interior.

As shown in Figs. 9 and 10, I may reverse the position of the lips shown in Fig. 8 by making the curve the inner surface and the straight surface the outer surface. In this case the notches will be cut in the straight outer surface and the lips when held together by the band *B²*, Fig. 10, will cause the inner curved surface to assume a straight line, with the lips *L L* adjacent to each other and the mouth closed.

It is important that the lips have a greater diameter on a center line at right angles to the line of contact and that they taper toward the end of the line of contact, as this insures complete and strong closure to prevent egress of material as well as the ready opening of the mouth under proper pressure.

I claim as my invention—

1. A self-closing mouth for a bag comprising an elastic tube, flexible lips at the mouth of said tube, said lips having tapering ends, and straight adjacent inner surfaces, and elastic means for holding said surfaces in contact, substantially as described.

2. A self-closing mouth for a bag, comprising lips, shaped as segments of a circle, and

an elastic tube secured to said lips adapted to hold said lips closed, substantially as described.

3. A self-closing mouth for a bag, comprising lips, elastic means for keeping said lips closed, an elastic tube secured to said lips in combination with two flanges at the end of said tube, substantially as described.

4. A self-closing mouth for a bag, comprising lips shaped as segments of a circle, an elastic tube surrounding and secured to said lips, whereby the lips are held closed under its tension, substantially as described.

5. A self-closing mouth for a bag, comprising two lips shaped as segments of a circle and slitted in their outer sides, and elastic means surrounding said lips.

6. A self-closing mouth for a bag, comprising lips having straight outer slitted edges, and an elastic means surrounding said lips to curve said outer edges and close the in-

ner edges on each other, substantially as described.

7. A closure for a bag comprising a self-closing mouth and a pair of flanges, an elastic tube connecting them, the flanges adapted to frictionally grasp and hold the mouth of a bag between them, substantially as described.

8. A self-closing mouth for a bag, comprising a pair of lips flexible throughout, meeting on a straight center line and widest at a central line at right angles to said meeting-line, the lips tapering toward the ends and an elastic tube adapted to hold said lips together, substantially as described.

In testimony whereof I have signed my name to this specification in the presence of two subscribing witnesses.

GEORGE W. WILLIAMS.
